UNITED STATES PATENT OFFICE.

ROBERT B. SCHULTHEIS, OF BROOKLYN, NEW YORK.

TIME-CONTROL MECHANISM FOR RADIORECEIVERS.

Application filed August 31, 1926. Serial No. 132,798.

My invention relates to mechanism, preferably in the form of an attachment applicable to a standard radio receiver, for effecting the starting or stopping of the receiver 5 at a predetermined time.

In a practical embodiment of the invention, as represented by the example here given, I provide clock work usually in the form of a standard alarm clock, with a 10 suitable base for removably mounting it upon the cabinet of a standard radio receiver, together with other fittings or connections detachably applicable to the radio receiver by means of which the operation of 15 the alarm mechanism operates the controlling switch of the radio receiver to open or close the switch circuit and start or stop reception of a broadcast or other radio "signal" of the frequency to which the receiver 20 is tuned.

Usually I prefer to so arrange the mechanism that it operates to "start" the receiver, but after considering the following description it will be evident that by simple re- 25 arrangement of parts the mechanism will be effective to stop the receiver, that is, to discontinue reception.

The characteristics and advantages of the invention are further sufficiently explained 30 in connection with the following detail description of the accompanying drawing, which shows one representative embodiment 35 of the invention. After considering this example, skilled persons will understand that many variations may be made, and I contemplate the employment of any structures 40 that are properly within the scope of the appended claims.

In the drawings:

40 Fig. 1 is a view in perspective of one end of a typical or standard radio receiver with my time control mechanism or attachment, in one form, applied thereto.

Fig. 2 is an end elevation.

45 Fig. 3 is a fragmentary detail.

Fig. 4 is a detail of a modified switch lever.

50 Preferably, I provide timing mechanism in the form of a standard alarm clock 1 which is secured to a base board 2 in any convenient way, as by a clamping strap 3. At its rear edge the base board has a depending flange 4. The alarm winding key 5 or its shaft is provided with a pulley 6 and a cord 7 is secured to and wound upon 55 the pulley.

The radio receiver R, representing any known or standard type of such apparatus, has any known or common type of "starting" switch S, the function of which is to 60 close and open (usually) the filament circuit and so to render the receiver operative or inoperative. These switches are of different types. The type shown is an ordinary push-pull switch such as is employed 65 in many radio receivers and it will be evident that the mechanism or attachments hereafter described may readily be modified to actuate switches of other types, such as turn or toggle switches. The push-pull 70 switch S is usually secured to the radio panel P by a knurled nut 10. This nut may be removed and a fulcrum bracket 11 constituting part of my invention applied. This bracket has a base 12 apertured to fit around 75 the projecting switch sleeve and the base is then secured against the panel by reapplying nut 10 and turning it up tight. The switch stem terminating in the knob or button 13 reciprocates through the switch 80 sleeve. A clamp 14 is detachably applied or connected to the switch knob or button and is also connected by a link 15 to the lower end of lever 16 which is fulcrumed between 85 flanges 17 of the horizontally extending part of bracket 11. The upper end of the lever is connected to cord 7 above mentioned, and the cord between pulley 6 and the lever, is guided or directed in any convenient way, for example, by one or more pulleys 20, these 90 pulleys or cord guides being arranged as necessary or convenient to properly direct the cord and apply the pull provided by rotation of the alarm winding key 5 or its stem through the cord to the lever. 95

The parts such as the clip or clamp 14, bracket 11 and lever 16, may vary considerably. Conveniently, they are formed of sheet metal. The switch clamp 14 has jaws 21 notched to embrace and fit about the 100 switch stem behind the button or knob 13 and secured detachably in this position by a clamp-nut and screw 22. The parts of the invention mechanism, such as the clamp, bracket and lever, may be readily detached 105 in an obvious way if it is not desired to use the time mechanism, or they may be left in position without interfering with normal control of the receiver.

The clock with its base are placed upon 110 the top of the radio cabinet in about the position shown, with due reference to the

position of the switch S. The rear flange 4 then prevents forward displacement of the clock and its base under the influence of the cord pull.

5 It is usually desired to start the receiver at a pre-determined time for the reception of a certain "program" from a broadcast or other radio transmitting station. The receiver is of course, tuned to the station 10 frequency or wave-length. The alarm indicator of the clock 1 is set for a time just previous to commencement of the "transmission" by the broadcast or other station, or to a time at which it is desired to begin 15 the reproduction of the transmitted program. The alarm wind key is then turned to wind up the alarm mechanism and in this operation the cord 7 may be drawn off of the pulley 6 with accompanying outward movement of the upper end of lever 16 to permit 20 the switch knob 13 to be pushed in so that the receiver is in inoperative condition. Then at the appointed time the alarm mechanism trips the alarm; the alarm wind key 25 5 or its stem revolves, cord 7 is wound upon the pulley 6 and the cord pulley controlled by the guides such as pulley 20, is applied to the upper end of the lever, the lower end of which is thus moved outward and clamp 30 14 acting upon the switch knob pulls out the switch and starts the radio receiver to reproduce the transmitted program.

Evidently if the switch S is so arranged 35 that it will break the receiver controlling circuit when pulled out, the described operation will serve to stop reception instead of starting it; otherwise, with the switch arranged as usual to open the circuit when it is pushed in, the lever and linkage arrangement 40 may be so modified that operation of the clock mechanism will push the switch stem in and stop reception.

An important feature of the mechanism, 45 as shown and described, is that it is arranged as an attachment so that the various parts may be easily and quickly applied to a standard radio receiver without altering the receiver mechanism or injuring it in any way, and especially the clock with its base 50 and base flange may be easily applied by merely placing it upon the receiver in the position shown, and it may be as easily removed if, for example, it is desired to raise

the top of the receiver cabinet to gain access to the interior.

55

A standard alarm clock is desirably employed, because such clocks are easily procurable at low cost and the entire apparatus therefore may evidently be economically made and sold at a moderate price.

60

Evidently a small number of turns of the pulley is sufficient to effect desired movement of the receiver switch. Thereafter, by reason of connection of the lever to the switch knob tautness of the cord it is impossible for the alarm winder to rotate further. Therefore the audible alarm mechanism of the clock will give only a short signal continuing up to the time when the receiver is "turned on" and then the audible alarm clock signal is discontinued by preventing further rotation of the alarm winder. In this way the invention prevents annoyance that would otherwise be caused by continuation of the alarm signal after 75 the radio-receiver is in operation.

70

Fig. 4 shows a lever 16^a applied to the knob 13^a of a rotary or "turn" switch. In this case the cord 7 may go from the lever and over the upper edge of the cabinet, to 80 the guide 20, and thence to the pulley.

I claim: —

Time control mechanism readily applicable to and removable from a cabinet containing electrical apparatus, said cabinet 85 having a movable switch element on its front wall, said mechanism comprising clock mechanism having alarm means including an alarm winder, a base for said clock mechanism adapted to rest upon the top of said 90 cabinet, a depending flange connected to the base and adapted to engage against the rear of said cabinet and resist forward displacement of the base and the clock mechanism 95 thereon, and a pulley on the alarm winder, a cord connected to the pulley, a lever arranged for connection to said switch element and also connected to the cord, and cord guides, whereby rotation of the alarm winder winds the cord upon the pulley and 100 operates the lever to move said switch element.

Signed at New York city in the county of New York and State of New York this 19th day of August A. D. 1926.

ROBERT B. SCHULTHEIS.
